Attorney

UNITED STATES PATENT OFFICE.

HENRY JOSEPH ZELING, OF MILWAUKEE, WISCONSIN.

DIRECTION-INDICATOR.

1,279,210.

Specification of Letters Patent. Patented Sept. 17, 1918.

Application filed January 12, 1918. Serial No. 211,568.

To all whom it may concern:

Be it known that I, HENRY J. ZELING, a citizen of the United States, residing at Milwaukee, in the county of Milwaukee and State of Wisconsin, have invented certain new and useful Improvements in Direction-Indicators, of which the following is a specification, reference being had to the accompanying drawings.

10 This invention relates to certain improvements in direction indicators and has relation more particularly to an indicator specially designed and adapted for use in connection with a vehicle and it is an object 15 of the invention to provide a novel and improved device of this general character which may be operated with convenience and facility to indicate the direction of turn to be made and which notice or indication 20 may be readily observed by a second vehicle following or traveling toward the vehicle provided with the indicator.

It is also an object of the invention to provide a novel and improved device of this 25 general character including a housing supported to one side of a vehicle and in which a slideable member is arranged and which member is mounted for movement in a direction transversely of the vehicle and which 30 may be extended beyond opposite ends of the housing, said slide when extended beyond either end of the housing serving to give notice of a direction of turn about to be made.

35 The invention consists in the details of construction and in the combination and arrangement of the several parts of my improved direction indicator whereby certain important advantages are attained and the 40 device rendered simpler, less expensive and otherwise more convenient and advantageous for use, as will be hereinafter more fully set forth.

The novel features of my invention will 45 be hereinafter definitely claimed.

In order that my invention may be the better understood, I will now proceed to describe the same with reference to the accompanying drawings, wherein:

50 Figure 1 is a view in elevation illustrating an indicator constructed in accordance with an embodiment of my invention, the coacting portion of the vehicle body being indicated by dotted lines;

Fig. 2 is an enlarged longitudinal sectional view taken through the device with certain of the parts in elevation; and

Fig. 3 is a transverse sectional view of the indicator as herein set forth.

As disclosed in the accompanying drawings B denotes a body of a vehicle which has positioned beyond the side thereof a housing H with the longitudinal axis of said housing extending in a direction transversely of the body B. The inner end portion of the housing at the top and bottom thereof is provided with inwardly directed arms 1 suitably secured as at 2 to the side of the vehicle whereby it will be perceived that the housing H is supported in a fixed 70 position to one side of the body B.

The opposite ends of the housing H are open and slidably arranged within the housing H is the hollow member or body M having its side faces 3 preferably transparent and each of said side faces 3 has produced therefrom a pair of reversely directed arrows A having the heads 5 thereof outwardly directed. The arrows A are also preferably formed of transparent material 80 and it is particularly desired that such arrows be red in color so that they may be more readily observed when the member or body M is extended.

The body or member M is of a length 85 substantially equal to the length of the housing H so that the body or member M may be entirely positioned within the housing and which is the normal position of said body or member M. It is particularly desired that the housing H extend beyond the left side of the body B and should it be desired to make a turn to the right the member or body M is moved toward the body B to expose the arrows A at the right hand portions of the faces 3. Should it be desired to give notice of a turn to the left, the body or member M is moved in the opposite direction to dispose a second set of arrows A. The bottom of the housing H is provided 100 with the longitudinally disposed slot 6 through which extends the hollow arm 7 depending from the bottom of the body or member M at substantially the center thereof. In communication with the arm 7 and connected thereto is the elongated hollow rod 8 extending inwardly toward the body and terminating in the handle or hand grasp

9. The rod 8 is of a length to extend beyond the inner end of the housing H at all times so that the handle or hand grasp 9 may be readily and conveniently gripped or engaged by the occupant of the body B and as is particularly illustrated in Fig. 1 it is preferred that the rod 8 be of a length to partially overlie the body B irrespective of the position of the member M. Mounted 10 within the body or member M above the depending arm 7 is a socket 10 electrically connected with a suitable source of energy by the conductors *a* disposed through the arm 7 and the rod 8. Engaged with the socket 10 is the lamp 11 of the well-known incandescent type. When the electrical circuit is closed the illumination afforded by the lamp 11 will result in the arrows A being readily designed when the body or member M has 20 been moved to expose a set of arrows beyond an end of the housing H.

From the foregoing description, it is thought to be obvious that a direction indicator constructed in accordance with 25 my invention is particularly well adapted for use by reason of the convenience and facility with which it may be assembled and operated, and it will also be obvious that my invention is susceptible of some 30 change and modification without departing from the principles and spirit thereof and for this reason I do not wish to be understood as limiting myself to the precise arrangement and formation of the several 35 parts herein shown in carrying out my in-

vention in practice except as hereinafter claimed.

I claim:

A direction indicator for vehicles comprising a housing open at opposite ends and adapted to be supported a predetermined distance beyond a side of the vehicle, a member slidably engaged within the housing, said member being of a length substantially equal to the length of the housing whereby said member may be inclosed within the housing, the opposite faces of said member adjacent the opposite ends thereof being provided with oppositely directed indicating symbols, and a rod engageable with the member substantially midway thereof for partially extending the member beyond either end of the housing for exposing the indicating symbols carried by an end portion of the member and concealing the indicating symbols carried by the opposite end portions of the members, said rod being arranged exteriorly of the housing H and having a portion extending inwardly thereof, said rod being of a length to terminate inwardly of the housing irrespective of the position of the member M relative to the housing.

In testimony whereof I hereunto affix my signature in the presence of two witnesses. 65

HENRY JOSEPH ZELING.
